UNITED STATES PATENT OFFICE.

FRANK T. BOGARD, OF OAKLAND, CALIFORNIA, ASSIGNOR TO RODNEY H. MARCHANT, OF OAKLAND, CALIFORNIA.

TOILET FLUSH VALVE.

Application filed January 29, 1923. Serial No. 615,719.

To all whom it may concern:

Be it known that I, FRANK T. BOGARD, a citizen of the United States, residing at Oakland, county of Alameda, State of California, have invented certain new and useful Improvements in Toilet Flush Valves; and I do declare the following to be a full, clear, and exact description of the same, reference being had to the accompanying drawings, and to the characters of reference marked thereon, which form a part of this application.

This invention relates to improvements in flush valves, particularly for toilet purposes, and especially represents an improvement over the type of valve shown in the patent to Charles H. Gunn, No. 1,407,998, February 28th, 1922, which valve is intended to be used in connection with a pair of tanks, or a divided tank, connected to a supply of water under pressure, and arranged to allow either tank to be filling while the other is being emptied for flushing.

The principal object of the present invention is to construct a valve of the above named type so that while the principle of operation and the results obtained are the same as before, a tendency to leakage, which was evidenced during experiments with the original valve, and which was due to the arrangement of the various ports, has been largely if not entirely eliminated.

One great trouble brought about by the said previous arrangement of the ports was the abrasive action of the grit present in the usual water supply, and which cannot be eliminated. With my improved port arrangement however, I prevent the water at the intake ports, which is under pressure, from coming into contact with any great area of surface of the turnable valve plug, or its seat, prior to the entrance of the water into the tank, and when it is withdrawn therefrom, the grit, etc., has largely settled, and the abrasive action of the remainder largely eliminated owing to the freedom with which the water may escape.

Trouble was also previously experienced with the plug tending to stick in its seat, or else to be so loose a fit that leakage was had, and another object of my invention therefore is to so mount the plug that while it may be adjusted to have a snug fit in

its seat, it cannot back out, and also any tendency to stick is absent.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims:

In the drawings similar characters of reference indicate corresponding parts in the several views:

Fig. 1 is a side view of my improved valve, showing the same mounted in connection with its tanks and a toilet.

Fig. 2 is a sectional plan of the valve.

Fig. 3 is a cross section taken on line 3—3 of Fig. 2.

Fig. 4 is a cross section taken on line 4—4 of Fig. 2.

Referring now more particularly to the characters of reference on the drawings, the numeral 1 denotes a cylindrical and taper-bored casing having on its under side an outlet 2 adapted for connection to the flush-pipe 3 of a standard toilet 4.

Projecting from opposite sides of the casing and in the same transverse plane as the outlet 2 are ports or passageways 5 and 6, the port 5 being adapted for connection to a pipe 7 leading to a pressure tank 8 while the port 6 is likewise adapted to be connected to a similar but independent tank (not shown).

A bypass port 9 leads from the port 5 to communicate with the casing-bore beyond the said port 5, while a bypass 10 similarly leads from the port 6 to the casing bore beyond the latter port and in transverse alignment with the termination of port 9.

On top of the casing in transverse alignment with the bypass ports 9 and 10 and located centrally therebetween is an intake port 11 adapted to be connected to a pipe 12 leading to a supply of water under pressure.

Turnably fitted in the casing is a taper plug 13 having on its small end a stem 14 which projects through a stuffing-box member 15 on the adjacent end of the casing.

Removably secured on the stem outwardly of the member 15 is a handle 16 by means of which the plug may be turned, said handle having a sleeve 17 which projects over and

conceals the stuffing box, the sleeve having an interior lug 18 movable between lugs 19 fixed with respect to the casing, whereby the extent of movement of the lever and plug 5 is definitely limited.

The casing projects beyond the plug at the other end and is tapped to receive a screw cap 20 in which is adjustably mounted a screw 21 the inner end of which is pointed 10 or cone shaped to seat in a socket provided in the adjacent end of the plug, the screw of course being in axial alinement with the plug.

By this means the plug may be adjusted to 15 seat to a nicety in the casing, and any wear may be taken up as it occurs, without any danger of the plug then wedging in its seat, or of its backing away from the same, since when once set, it is definitely held in a fixed 20 position. At the same time, nothing has been provided to interfere with the ready turning of the plug as required.

The plug 13 has a flushing passage 22 adapted to register with the port 5 and with 25 the outlet 2. Another flushing passage 23 in the plug, in transverse alinement with the passage 22 and spaced therefrom throughout, is adapted to register with the port 6 and with the outlet 2, the adjacent 30 terminations of said ports and passages being preferably rectangular in cross section and of the same area.

The positioning of the passages relative to 35 each other and to the ports 5 and 6 is such that when either passage registers with its casing port, the other passage is blinded at both ends by the casing wall, its casing port being then centrally between the ends of said passage.

40 Located in the plug in transverse alinement with the by-pass ports 9 and 10 and intake port 11 are other spaced intake passages 24 and 25 adapted to register with the ports 9 and 10 respectively and alternately 45 with the common port 11. These passages are so arranged relative to the passages 22 and 23 that when the latter is positioned to open communication between the port 10 and outlet 2, the passage 24 is then positioned to open communication between the 50 ports 9 and 11, and vice versa, the result of course being that as water is flowing into one of the tanks from the intake pipe 12, water from the other tank is discharging 55 into the bowl 4.

By means of the above described construction and arrangement of parts, the water entering the plug from the supply pipe will pass directly to either tank without coming in contact with the bored surface of the plug or casing except over that portion of the plug between the ends of the flushing passage on that side, which covers the corresponding port 9 or 10, and 65 which is not then in use.

However since the water is flowing away from this exposed surface and not toward, no abrasion of the latter due to any grit in the water will be evident.

It will also be noted that when either 70 passage 9 or 10 is positioned to function, no bearing surface against which the rush of water can impinge and deposit foreign matter is exposed.

Further, there is at all times, a seal-surface, of the plug and casing, all around the same and between the intake and flushing passages and ports, and separating the incoming and outgoing flow of water, and never in contact with any water, this feature materially aiding in the prevention of abrasion and the consequent leakage between ports.

75 Bleed holes 26 are drilled from both ends of the plug to the passages 22 and 23, these 80 preventing locking of the plug in the casing in the event of any pressure of water getting behind the end of the plug.

85 From the foregoing description it will be readily seen that I have produced such a 90 device as substantially fulfills the objects of the invention as set forth herein.

95 While this specification sets forth in detail the present preferred construction of the device, still in practice such deviations from such detail may be resorted to as do not form a departure from the spirit of the invention, as defined by the appended claims.

Having thus described my invention, what 100 I claim as new and useful and desire to secure by Letters Patent is:

1. A valve comprising a casing, a pair of transversely opposed ports therein, passageways leading outwardly from said ports, an outlet from the casing, by passes leading from the passages to the interior of the casing beyond the ports, an intake leading to the casing, a plug turnably mounted in the casing, and port means in the plug for alternately allowing water to flow from one passage and port to the outlet while allowing water to flow from the intake into the by-pass leading to the other passageway.

105 2. A valve comprising a casing, a pair of transversely opposed ports therein, passageways leading outwardly from said ports, an outlet from the casing, by passes leading from the passages to the interior of the casing beyond the ports, an intake leading to 110 the casing and a plug turnably mounted in the casing and provided with port means allowing communication between either one of the passageways and its port and the outlet, and also between the intake and the bypass leading to the other passageway at the same time.

115 3. A valve comprising a casing, a pair of transversely opposed ports therein, passageways leading outwardly from said ports, an 120

- outlet from the casing intermediate said ports, by passes leading from the passages to the interior of the casing beyond the ports, an intake leading to the casing between the 5 bypass connections therewith, a plug turnably mounted in the casing, independent passages through the plug for allowing communication between the outlet and the ports alternately, and independent passages 10 through said plug for allowing communication between the intake and the bypasses alternately and in reverse order with respect to the communication of said ports with the outlet.
- 15 4. A valve comprising a casing, a pair of opposed ports positioned in a common transverse plane, passages leading outwardly from the ports, an outlet from the casing intermediate the ports and in the same trans- 20 verse plane, bypasses leading from the pas-
- sages to the casing beyond the ports and terminating in said casing in spaced relation and in a common transverse plane, an intake to said casing in the same plane and intermediate said bypass terminations, 25 a plug turnably mounted in the casing, spaced passages through the plug in transverse alinement with the ports and adapted to register alternately with said ports and with the outlet, and independent passages 30 through the plug in transverse alinement with the by pass terminations and with the intake, arranged to register alternately with said by passes and the intake in opposite order to the registering of the first named 35 plug passages with the ports and outlet.

In testimony whereof I affix my signature.

FRANK T. BOGARD.
